CORE RECOVERY RECORDER

Benjamin W. Sewell, Tulsa, Okla., assignor to
Standard Oil Development Company, a corpo-
ration of Delaware

Application October 25, 1947, Serial No. 782,097

2 Claims. (Cl. 346—127)

1

The present invention is directed to an apparatus for use in the drilling and collection of cores of a subterranean formation.

In the drilling of earth bore holes, particularly those drilled for oil, it is common practice to secure cores of a subterranean formation to be studied. These are commonly secured by using what is known as a core bit, which is similar to the ordinary bit except that it has a large central opening through which a core can pass upwardly into a collection chamber. Various types of core barrels have been devised for use in this operation. A conventional type is known as the wire line type. This type of barrel is lowered on a wire line into a drill stem to a seat just above the drill bit. As the core is cut it passes up into the barrel and is collected and eventually brought to the surface at the end of a wire line. Other particular types of core barrels which have been developed are those known as pressure core barrels which secure a core of a subterranean formation under the pressure existing in the formation, and bring the core to the surface without loss of that pressure.

In all coring operations difficulty is encountered by reason of the fact that the operator is so far from the scene of the actual coring. He brings his core barrel to the surface and finds in it a certain amount of core but he has no assurance at all as to the part of the formation, considered vertically, represented by that portion of core. In other words, he may drill a twenty foot core out of a formation and bring to the surface only a few feet. He would usually assume that he has lost the bottom 18 feet of core and that the sample he recovered represented the top two feet. It is quite possible, however, that the first several top feet of the core may not be recovered by reason of the fact that it crumbles and is washed away. Therefore, if he has recovered only a few feet out of 20 feet, he does not know whether it is the top 2 feet, the bottom 2 feet, or something in between.

The principal object of the present invention is to provide a device for use in conjunction with coring operations to supply information as to the course of the coring operation.

A more specific object of the present invention is to provide a device of the character described in which there is made a continuous record of the rate at which core enters a core barrel and of the height it reaches in the core barrel.

Other objects and advantages of the present invention will appear from the following detailed description of the accompanying drawing in which:

Fig. 1 is a vertical section through a core barrel containing the device of the present invention; and

Fig. 2 is a plan view of the device.

5 Referring to the drawing in detail, numeral 1 designates the wall of a core barrel. Ordinarily a core barrel is provided at its lower end with a plug which is attached to the wall by shear pins. This plug serves to keep out foreign matter from 10 the core barrel until the actual coring operation begins. As the core is cut and starts to move upwardly it shears off the pins holding the plug, and pushes the plug back up into the core barrel so that room is made therein for the core. The 15 device of the present invention can serve the purpose of the ordinary plug. Thus, the device of the present invention is a cylindrical casing 2 and is provided at its lower end with a shear ring 3 which is connected by shear pins to the lower end 20 of the core barrel.

The cylindrical body has a central chamber 4, in the lower end of which is arranged a spring motor or other type of motor 5 having a shaft 6 journaled in the partition 7 and connected above 25 the partition with one end of a drum 8 which rotates with the shaft and has fixed to its inner wall a chart in the manner usual with recording devices of this type.

Fixed to the upper wall of the chamber 4 is 30 a post 9 which carries at its lower end a plate 10 in which is journaled a threaded rod 11 which extends upwardly through the upper wall of the chamber 4 into a slot 12 at the upper end of the cylindrical member 2. The upper end of the member 11 has secured thereto a worm 13 which 35 is in engagement with a gear 14 carried by a shaft 15, to which is also pinned a large wheel 16 having a knurled surface. This wheel is of sufficient diameter to press against the wall of the core barrel under the influence of spacing 40 spring members 17 suitably disposed about the periphery of the cylindrical member 2.

In threaded engagement with the lower end of the member 11 is a follower 18 carrying at its 45 end a stylus 19 which operates on the paper chart on the inner wall of the drum 8. This follower is also slidably mounted on the post 9 whereby rotation of the element 11 causes the follower to move up and down vertically.

Below the cylindrical chamber 4 the cylinder 2 has a second slot 20 in which is journaled a wheel 21 corresponding to the wheel 16. This wheel is present only to balance the device.

When a coring operation is to be performed the device described is fixed in the core barrel in 50 the position ordinarily occupied by the plug.

The clockwork drive is started in operation. As the core enters the chamber it pushes the device upwardly. As the device moves upwardly the knurled wheel 16 is caused to rotate and this in turn rotates the element 11, causing the stylus to move upwardly on the chart. If, during the coring operation some of the core is lost as by being crumbled and washed away, it does not cause the stylus to move up. Again, after the coring operation is completed and the core assembly is brought to the surface, if there is any core lost from the barrel which would result in the recording device moving downwardly the chart will give an indication of this occurrence. The distance to which the stylus rises on the chart indicates the amount of core which enters the barrel and the slope of the trace on the chart gives an indication of the rate at which the core entered the barrel.

At the same time the driller records at the surface the drilling rate, or the rate at which the bit moves in to the formation. By comparing the drilling rate log with the core movement log, the operator can reconstruct what happened during the coring operation. For example, if the drilling rate log shows a penetration of one foot per minute at the beginning of the coring operation and no core movement into the core barrel is recorded during this period, the operator knows that the top portion of the core was lost.

The nature and objects of the present invention having been described and illustrated, what is claimed as new and useful and is desired to be secured by Letters Patent is:

1. A core device comprising a core barrel, a sealed cylindrical chamber slidably mounted in said barrel and normally resting on the bottom thereof, a cylindrical chart-holding means mounted for rotation in said chamber and carrying a chart on its inner surface, means for rotating said chart-holding means at predetermined rate, a threaded rod rotatably mounted in a vertical position within said chamber, a follower threadedly engaged with said threaded rod, a

stylus mounted on said follower and adapted to contact said chart, a wheel carried by said cylindrical chamber in a position engaging said wheel with the inside wall of said core barrel so as to rotate said wheel when said chamber is caused to slide lengthwise of said barrel, means for transferring motion of said wheel to said threaded rod and spring means affixed to said chamber urging said wheel into contact with the wall of said core barrel.

2. A recording device for recording the rate of recovery of a core in a core barrel which comprises a cylindrical casing adapted to fit slidably within a core barrel, a cylindrical chart-holding means mounted for rotation in said casing and carrying a chart on its inner surface, means for rotating said chart-holding means at a predetermined rate, a threaded rod rotatably mounted in a vertical position within said casing, a follower threadedly engaged with said threaded rod, a stylus mounted on said follower and adapted to contact said chart, a wheel carried by said casing in a position adapted to engage the wheel with the inside wall of a core barrel so as to rotate said wheel when said casing is caused to slide lengthwise of said core barrel, means for transferring motion of said wheel to said threaded rod and spring means affixed to said casing and adapted to urge said wheel into contact with the inside wall of a core barrel.
